LINE PULSE MODULATOR FOR MULTI-
CHANNEL TRANSMITTERS

Philip C. Bettler, Boston, and Howard D. Doolittle,
Cambridge, Mass., assignors, by mesne assignments,
to the Government of the United States
of America as represented by the Secretary of
War

Application February 3, 1945, Serial No. 576,114

4 Claims. (Cl. 250—17)

1

The present invention relates to radar object-detection systems, and more particularly to a circuit arrangement for simultaneously operating a plurality of high-frequency wave generators in a radar system.

In certain pulse-echo object-detection systems entailing the use of two or more antennas, it is required that more than one magnetron operating from the same pulse modulator be employed. While all the magnetrons are synchronized to transmit pulses in coincidence, they do not necessarily have the same impedance, especially when the magnetrons are adapted to operate at different frequencies.

Accordingly, it is an object of this invention to provide a single line pulse modulator for energizing a plurality of transmitters having different impedances, the energization of all transmitters being simultaneous.

An additional object of this invention is to provide a single line pulse modulator for energizing a plurality of parallelly connected radar transmitters having different impedances and different operating frequencies, the modulator simultaneously energizing all transmitters preferably for equal lengths of time and capable of furnishing any desired preselected power distribution among the transmitters.

For a better understanding of the present invention, as well as other features thereof, reference is had to the following description to be read in connection with the accompanying drawing schematically showing a preferred embodiment of a radar transmitter in accordance with the invention.

A plurality of magnetrons 10, 11, 12 and 13 are provided energized from a direct-current power source applied between terminal 14 and ground. The oscillations yielded by each magnetron are fed to separate antennas. Terminal 14 is connected through a choke coil 15 and a pulse-forming line 16 to one end of the primary winding of a pulse step-up transformer 17, the other end thereof being grounded. The secondary winding of transformer 17 is connected to the electrodes of magnetron 10. In a like manner, magnetron 11 is coupled to the power source through a pulse transformer 18 and a pulse-forming line 19, magnetron 12 is coupled to the power source through a pulse transformer 20 and a pulse-forming line 21, and magnetron 13 is coupled to the power source through a pulse transformer 22 and a pulse-forming line 23. The characteristic impedance of each connected pulse-forming line and associated transformer and switch 24 is made

2

equal to the impedance of the magnetron associated therewith. Stated differently the impedance of transformer 17 and the impedance of modulator switch 24 match the impedance of line 16, the matching being necessary to avoid any wave reflections, which cannot be tolerated in described circuits. The same relationship of impedances exists in the remaining parallel branches of the modulator. If desired, the transformer may be eliminated, in which case the impedance of the pulse-forming line is made equal to the impedance of its associated magnetron and switch 24.

A modulator switch 24 is connected between ground and the junction of choke 15 and pulse-forming line 16, said switch being of any suitable construction, as for example, that of the fixed or rotary spark gap type, or of the thyratron type. Each of the pulse-forming lines 16, 19, 21 and 23, which may be either of the Guillemin line type 20 (as shown), or the ordinary artificial transmission line, is charged through choke 15 and the primary winding of its associated transformer. The inductance of choke 15 and the capacitance of the line form a resonant circuit so that the 25 voltage across the line tends to oscillate. At the peak of the first positive swing, the line is charged to a voltage considerably higher than the D.-C. supply voltage. At this instant, a triggering pulse is applied by a source 25 to modulator switch 24 rendering it conductive, thereby discharging each 30 of pulse-forming lines 16, 19, 21 and 23 through its associated transformer primary winding and applying concurrent surges of energy to magnetrons 10, 11, 12 and 13.

As seen in the drawing, only one modulator switch 24 is employed which insures that the pulses will be simultaneous, and since the charging condensers in each of pulse-forming lines 16, 19, 21 and 23 assume the same potential, the 40 energy delivered to each of the loads is the same. Thus, the power to the magnetrons 10, 11, 12 and 13 will be divided evenly or in certain proportions if so desired, the latter being accomplished by adjusting the parameters of the individual lines. 45 Another advantage of this arrangement resides in the fact that the storage capacitors of the pulse-forming lines, being charged in parallel, need be subjected only to the voltage required for one magnetron, thereby giving an extended life 50 to the pulse-forming lines or permitting a less expensive construction. It is to be noted that the amplitude of the peak current across modulator switch 24 is materially increased, hence it must be constructed with this factor in mind.

55 While there has been described what is at pres-

ent considered a preferred embodiment of the invention, it will be obvious to those skilled in the art that various changes and modifications may be made therein without departing from the invention, and it is aimed in the appended claims to cover all such changes and modifications as fall within the true spirit and scope of the invention.

What is claimed is:

1. In a multi-channel pulse transmitter, a plurality of magnetrons, a corresponding plurality of pulse-forming networks, each of said networks being coupled to its respective magnetron, means for charging in parallel said plurality of networks, and means for periodically and simultaneously discharging said plurality of networks to deliver a pulse of energy from the respective network to the magnetron coupled to said network.

2. A multi-channel transmitter including a plurality of transmitters, a corresponding plurality of artificial lines, a like plurality of coupling means, one terminal of each line being coupled to its respective transmitter through the corresponding coupling means, a source of direct current potential, a choke coil connected with one end to one terminal of said source and with the other end to the remaining terminals of said artificial lines, a connection between the other terminal of said source and all of said coupling means, whereby said source is capable of simultaneously charging all of said artificial lines, a single modulator switch shunting all of said lines and all of said coupling means, and a source of periodic pulses connected to said switch for periodically closing said switch, whereby all of said lines are simultaneously discharged through said switch and through the respective coupling means.

3. A multi-channel pulse transmitter as defined in claim 2 in which the parameters of said artificial lines, switch and coupling means are made to produce reflectionless discharges of said lines.
5. 4. In a multi-channel transmitter capable of transmitting simultaneously a plurality of pulses of equal duration and substantially equal power, a plurality of parallelly connected transmitting channels, a corresponding plurality of pulse-forming networks having equal capacities, a corresponding plurality of means for coupling each of said networks to its respective channel, a source of charging potential in parallel connection with said plurality of networks and said means, and a single modulator switch common to all of said networks and said coupling means, said switch periodically and simultaneously discharging said plurality of networks through said means.
